UNITED STATES PATENT OFFICE.

CHARLES FREBORG, OF KANKAKEE, ILLINOIS, ASSIGNOR TO PRICE AND TEEPLE PIANO COMPANY, OF CHICAGO, ILLINOIS, A CORPORATION OF ILLINOIS.

PNEUMATIC MOTOR.

1,183,862.

Specification of Letters Patent. Patented May 23, 1916.

Application filed November 18, 1913. Serial No. 801,608.

To all whom it may concern:

Be it known that I, CHARLES FREBORG, a citizen of the United States, residing at Kankakee, in the county of Kankakee and State of Illinois, have invented certain new and useful Improvements in Pneumatic Motors, of which the following is a specification.

The principal object of my invention is to provide a new and improved pneumatic motor suitable for use with pneumatic piano players.

Another object of my invention is to provide valve guides of improved construction for such a motor.

These and other objects of my invention will be made apparent in the following specification and claims, taken in connection with the accompanying drawings. In these drawings I have illustrated one specific embodiment of my invention, and I will now proceed to describe the same.

It will be understood that the invention is defined in the appended claims.

Referring to the drawings Figure 1 is a perspective view showing my improvement. Figs. 2 and 3 are perspective views of a valve and a guide therefor. Fig. 4 is a vertical sectional view of the motor. Figs. 5 and 6 are horizontal sectional views of the motor on lines 5 and 6 of Fig. 4.

My improved pneumatic motor comprises three pairs of oppositely acting bellows. The front fixed member of each bellows is designated 15 in the drawings, and the back oscillating member is 16. The oscillating members 16 are pivoted along a transverse axis 17, and the flexible material 18 extends across and incloses the individual bellows. A moderate vacuum is maintained by the main bellows of the blower—not shown in the drawings—and this vacuum is transmitted through the tube 19 to the conduit or chamber 30 that extends across in the fixed members 15. The lower end of each oscillating member has a lug 20, to which is pivoted one end of a link 21, the other end of each link engaging the cranked portion 22 of the shaft 23. The three cranks 22 are set 120° apart. Each link 21 has an offset 24 near its crank end, to which is pivoted one end of a link 25, the other end of said link being pivoted to the lugs 26 on the D-slide 32. Each fixed member 15 has a front face plate or slide plate 31, against

which the slide valve 32 lies. The opposed sliding surface may be lubricated with graphite. The upper bellows of each pair of bellows opens through ports 27 on the front plate 31, and the lower bellows of each pair opens similarly through ports 28. Also, the vacuum conduit 30 opens on the front plate 31 by ports 29, between the ports 27 and 28. The D-slide valve 32 has a recess 33 adapted when the valve 32 is at one end of its travel to connect the ports 29 with either set of ports 27 or 28. The slide valve has a longitudinally extending groove 34 on its outer face, and the guide rod 35 lies in that groove. The ends of the guide rod 35 are fixed in the respective member 15, as indicated at 36. Within the D-valve there is a longitudinal rib 37 to accommodate the external groove 34. The shaft 23 drives a sprocket wheel 38, which, in turn, drives a chain 39, and through it drives the mechanism intended to be driven—for example, the feed roll of a pneumatic player piano. When the D-valve 32 is at the lowermost position of its travel, it connects the ports 28 and 29, so that the vacuum in the tube 19 draws air from the lower bellows through ports into the chamber 30. This collapses the lower bellows referred to and oscillates the member 16, filling the upper bellows through the ports 27, which are open to the external air. Since the cranks 22 are 120° apart, and since the action on the links 21 is double-acting, it will be seen that a continuous rotation is given to the crank 90 shaft 23.

The guiding mechanism for the D-slide valves 32 is simple, and easy to construct and assemble, easily permits inspection for repairs, and is rugged and serviceable.

Making the ports double, that is of two holes side-by-side, has the advantage that it prevents the wood from curling or warping adjacent to the ports, and thus prevents the edges of the ports from catching the edge of the slide valve.

I claim:

1. In a pneumatic motor, a wall having ports therethrough, a slide valve having its inner side fitting over said wall and ports, said valve being provided with a longitudinal groove on its opposite side, a guide rod fitting in said groove having its ends projecting beyond said valve and attached to said wall, and engageable means carried by 110

said valve on each side of said groove whereby an operating member may be attached thereto to reciprocate said valve.

2. In a pneumatic motor, a wall with 5 ports therethrough, a slide valve over said ports, said valve having a longitudinal groove on its outer side, a fixed guide rod in said groove, lugs projecting from the outer side of the valve on each side of said 10 groove, and an actuating link with one end pivoted between said lugs.

3. In a pneumatic motor, a wall with ports therethrough, a slide valve over said ports, said valve fitting against the wall around 15 its edges and being recessed within said edges, said valve also having a longitudinal rib projecting into said recess and having a longitudinal external groove registering

with said rib, and a fixed guide rod in said groove.

4. In a pneumatic motor, a wall with 20 ports therethrough, a slide valve over said ports, said valve having a longitudinal groove on its outer side, and a guide rod in said groove, said guide rod projecting 25 each way beyond the ends of the groove and the ends of the guide rod being turned toward said wall and fixed in holes in the face of said wall.

20 In testimony whereof, I have subscribed 30 my name.

CHARLES FREBORG.
